UNITED STATES PATENT OFFICE

148,116

DESIGN FOR A SWITCH PLATE OR SIMILAR ARTICLE

Joseph A. Sposit, Philadelphia, Pa., assignor to
Blanding Corporation, Philadelphia, Pa., a cor-
poration of Pennsylvania

Application May 22, 1946, Serial No. 129,988

Term of patent 14 years

(Cl. D26—13)

To all whom it may concern:

Be it known that I, Joseph A. Sposit, a citizen of the United States, residing at Philadelphia, in the county of Philadelphia and State of Pennsylvania, have invented a new, original, and ornamental Design for a Switch Plate or Similar Article, of which the following is a specification, reference being had to the accompanying drawing, forming part thereof, in which:

Figure 1 is a front elevation of a switch plate embodying my design; and

Figure 2 is a side elevation thereof.

I claim:

The ornamental design for a switch plate or similar article, as shown.

JOSEPH A. SPOSITH.
